Primary Examiner — Rebecca Tsehay(74) *Attorney, Agent, or Firm* — Michael Best & Friedrich LLP(57) **CLAIM**

The ornamental design for a hair weaving device, as shown and described.

DESCRIPTION

FIG. 1 is a perspective view of the hair weaving device showing my new design;

FIG. 2 is a top view of the hair weaving device of FIG. 1; and,

FIG. 3 is a side view of the hair weaving device of FIG. 1. The dash-dot broken lines represent portions of the article that form no part of the claimed design. The dash-dot broken lines represent a boundary of the claimed design and form no part of the claimed design.

1 Claim, 2 Drawing Sheets(56)
